MOBILE CATERING BUILDING

Werner E. Carlson, San Gabriel, Calif., assignor to Loma Linda Food Company, Arlington, Calif., a corporation of California

Filed Mar. 30, 1962, Ser. No. 69,508

Term of patent 14 years

(Cl. D13—1)

FIG. 1 is a front side elevational view of a mobile catering building embodying my design;

FIG. 2 is a right end elevational view thereof;

FIG. 3 is a left end elevational view thereof;

FIG. 4 is a rear elevational view thereof; and

FIG. 5 is a top plan view thereof.

I claim:

The ornamental design for a mobile catering building, as shown.
